UNITED STATES PATENT OFFICE.

HOLLIS B. CRUM, OF CHICAGO, ILLINOIS, ASSIGNOR TO RAYMOND C. PENFIELD, OF NEW YORK, N. Y.

GRAVITY-CONVEYER.

1,089,537.

Specification of Letters Patent. Patented Mar. 10, 1914.

Application filed January 25, 1912. Serial No. 673,888.

To all whom it may concern:

Be it known that I, HOLLIS B. CRUM, a citizen of the United States, and resident of Chicago, in the county of Cook and State of Illinois, have invented an Improvement in Gravity-Conveyers, of which the following description, in connection with the accompanying drawings, is a specification, like letters on the drawings representing like parts.

This invention relates to conveyers adapted to receive lines of material and deliver the same to the desired destination on a roller system, the forwarding being usually and preferably effected by gravity.

The invention consists in an arrangement of the carrier system whereby it is adapted to separate an oncoming mass of the material or articles being forwarded and deliver the same to separated points with a like apportionment to each point.

While having other and more general fields of usefulness, the invention is well adapted for the loading of bricks into railroad cars, the conveying carrier extending into the car centrally thereof, and the branching arrangement of the present invention separating the bricks, turning one half to one end of the car and the other half to the other end; this arrangement thus making it possible for a single brick loading and supplying mechanism to deliver to both ends of the car at the same time, and thus enabling a double complement of men to be employed and the bricks handled twice as fast as before.

The invention will be better understood from the following detailed description, taking in connection with the accompanying drawings, and will be thereafter pointed out in the appended claims.

Referring to the drawings, Figure 1 is a plan view of an illustrative embodiment of the invention; Fig. 2 is an enlarged sectional view on line 2—2 of Fig. 1; Fig. 3 is an enlarged sectional view on line 3—3 of Fig. 1. Fig. 4 is a plan view of a slightly modified form with additional features; Fig. 5 is a front elevation thereof, and Fig. 6 is a perspective showing one side of this form of the apparatus.

The conveyer system for supplying the bricks and delivering them in more or less continuous lines may be of any desired type. In practice, such conveyer is usually

formed in sections of convenient size for assembling, with bars 10 forming end bearings for cylindrical rollers 11, these bars having their ends formed for suitable interlocking engagement, as typified by the brackets 12. The conveyer system in which the rollers 11 operate is of a width sufficient for forwarding a number of lines of bricks at once, six lines set edgewise being its capacity as herein shown. The rollers 11 deliver onto series of more or less conical rollers facing oppositely and forming conveyer ways 13, 14 which curve around to extend in opposite directions as seen at 15, 16. The first pair 17, 18 of these conical rollers 70 are preferably mounted on axes 19 in vertical alinement, and the next succeeding rollers 20, 21 may have the inner ends of their axes journaled in a common center rib 22 of the conveyer frame. After the 75 quarter-turn in either direction is made by the respective series of conical rollers, the oppositely extending straight portions 15, 16 are of course provided with cylindrical rollers 23.

To insure that the several lines of bricks, as fed along by the system of rollers 11, be assembled close together as seen at a in Fig. 2, I provide converging fences 24, 25 at either side of the conveyer, these fences being provided with series of vertically mounted rollers 26 whereby, although the bricks as supplied may be spread more or less on the conveyer, they are centered and bunched in close formation. Thus, as they 80 pass onto the first conical rollers 17, 18, half of them, shown as three, will swing around to the right and the other half to the left. Both ends of the car are in this way simultaneously supplied with bricks, so 85 that workmen can be piling up and filling in each end at the same time. The first pair of conical rollers 17, 18 preferably have their axes sloping slightly downward so that they present only a small raised center to the brick lines by reason of their conical form, and the succeeding conical rollers 20 have the inner ends of their axes gradually raised to the level of the outer ends thereof, so that the bricks pass over these and are 90 directed around the curves in either direction without difficulty.

The banking of the rolls which is essential for receiving the bricks as they are delivered by gravity at an angle, say of 15° 110

from the supplying conveyer, reducing the angle in this direction to 0, and delivering them to the oppositely extending conveyer portions with a proper incline at right angles to that of the supplying conveyer, is more clearly illustrated in Figs. 4, 5, and 6. As shown in these figures, the means for centering the oncoming stream of bricks and bringing them into close formation so that they will separate properly, is a single pair of relatively large vertically mounted rollers 27, 28 at either side of the conveyer way just back of its branching point on swinging arms 29, these arms being carried on vertical pivot posts 30 and held under yielding tension to press the rollers 27, 28 in against the brick lines by coil springs 31 fixed at one end to the vertical pivot posts 30 and with their other ends engaging the arms 29. This arrangement is preferable in that it better insures the proper centering of the brick lines for their even separation, these vertical presser rollers being adapted to yield to receive any uneven or irregular presentation of the brick lines, and being under sufficient tension to slide them laterally in either direction sufficiently to center and align them properly for their even separation. These views also show guard rails 32 mounted at the sides of the curving conveyer portions, such rails being fixed by suitable strap posts 33 or otherwise to the conveyer framing.

A suitable base frame for the branching conveyer sections is indicated conventionally at 34, this being of any preferred form, the details thereof forming no part of the invention. The extremities of the curving portions will in practice be joined to straight conveyer sections constituting the oppositely extending portions 15, 16 by suitable ear and pin fastenings 35 or otherwise.

The practice of my invention thus makes it possible to load cars with great celerity since, of course, the conveyer system of which the rollers 11 are the termination can supply the bricks at any desired rate and, by thus automatically effecting the division of the supply to both ends of the car at once, the entire car can be loaded in about half the time otherwise required.

While I have described my invention especially with reference to the loading of bricks into railroad cars, it is to be understood that this is merely illustrative and not restrictive and that the invention is adapted for the loading of any material or articles adapted to be handled by the conveyer set forth, either into railroad cars or

to any other destination where it is desirable to fill two separated spaces at the same time. Further, while my invention is well adapted for use as a part of a gravity conveyer system, it is to be understood as not limited thereto but is adapted for other uses.

Having described my invention, what I claim as new and desire to secure by Letters Patent is:—

1. An apparatus of the kind described, comprising a conveyer way for supplying lines of articles, said way having branching turns extending to diverging portions, and said turns having conical rollers arranged therein to automatically divide the lines of bricks and apportion them to said diverging portions.

2. An apparatus of the kind described, comprising a gravity conveyer way having branch turns leading to oppositely extending portions, said turns having mounted therein conical rollers adapted to divide lines of bricks and apportion them equally to said oppositely extending portions.

3. An apparatus of the kind described, comprising a sectional gravity roller conveyer having branching turns leading to oppositely extending portions, said turns and the conveyer portion adjacent thereto having banked conical rollers mounted therein in position to automatically apportion the lines of bricks between said oppositely extending portions and direct the same thereto.

4. An apparatus of the kind described, comprising a gravity roller conveyer way having branching turns leading to oppositely extending portions, said conveyer way having lateral guides for centering lines of bricks thereon and bringing them into close formation, and said turns having conical rollers arranged to apportion the lines of bricks therebetween.

5. An apparatus of the kind described, comprising a gravity roller conveyer way having branching turns leading to oppositely extending portions, said conveyer way having lateral spring presser means for centering the lines of bricks just before they reach said branching turns, and said turns having conical rollers arranged to apportion the lines of bricks therebetween.

In testimony whereof, I have signed my name to this specification, in the presence of two subscribing witnesses.
